UNITED STATES PATENT OFFICE

ARTHUR SAMUEL JOHN, OF STANTON, SOUTH WALES, ASSIGNOR TO DIM-DAZZLE (PARENT) COMPANY LIMITED, OF LONDON, ENGLAND

DESIGN FOR AN ANTIGLARE ATTACHMENT FOR WINDSHIELDS OF AUTOMOBILES

Application filed September 23, 1929, Serial No. 32,844, and in Great Britain November 16, 1928. Term of patent 3½ years.

To all whom it may concern:

Be it known that I, ARTHUR SAMUEL JOHN, a subject of the King of Great Britain and Ireland, residing at Stanton, Pembrey, South Wales, have invented a new, original, and ornamental Design for Antiglare Attachments for Windshields of Automobiles, of which the following is a specification, reference being had to the accompanying drawing, forming a part thereof.

Fig. 1 is a front view of an antiglare attachment showing my new design;
Fig. 2 is an edge view thereof.

I claim:—

The ornamental design for an antiglare attachment for windshields of automobiles, as shown.

In testimony whereof I hereunto affix my signature.

ARTHUR SAMUEL JOHN.
